CALCULATING MACHINE

Eugene S. Bush, St. Louis, Mo., assignor to Bush
Manufacturing Company, St. Louis, Mo., a cor-
poration of Missouri

Application February 6, 1936, Serial No. 62,598

11 Claims. (Cl. 235—61)

This invention relates to improvements in calculating machines, and more particularly to machines pertaining to and for use in the mathematical arts, and which are electrically or elec-
tro-mechanically operated.

A general object of the invention is attained in an improved and simplified agency for translating the movement of selecting keys or the like, to the totalling mechanism as such, this translating means consisting of an improved electro-mechanical device and a novel combination thereof with the keys and totalling mechanism of calculating machines.

A further object of the invention is attained in the simplification of the mechanism functionally connecting the keys and totalling apparatus, so as to require a minimum number of parts; to decrease the noise of operation heretofore attending the operation of calculating machines; to improve the key touch and to minimize the effort incident to key placement in connection with selecting operations. In utilizing the term "key" it is here intended to include any member presented to the operator for facultative manipulation in order to effect the totalling or other mathematical result.

More specifically stated in reference to the embodiment of the invention selected for disclosure, the invention has an object an improved use and application of electro-magnetic units or solenoids, for translating the key movements to the totalling, accumulating or other calculating mechanism as such.

In connection with the foregoing, it is an additional object of the invention to control the operation of the counting or calculating devices by means of solenoids, and to control the action of the solenoids in sequence by means of a master switch, which may itself be solenoid operated.

In connection with the foregoing, yet another object of the invention is so to construct a calculating machine, that the movement of an armature associated with each of the solenoids of one group or class, can be controlled at will by the operator of the machine; otherwise expressed, this object is attained in a preselection by the operator of the distance of armature travel in each of such solenoid coils.

In the foregoing statement of objects and in the ensuing description I have referred generally to the apparatus to which the invention pertains, as calculating machines. It is to be understood, however, that this term is used in its broader sense, so as to include practically all machines relating to the several mathematical

arts, for example, such machines as those for adding, subtracting, multiplying, dividing, as well as computing, counting, and bookkeeping machines. Since many or most of the machines of this general class consist essentially of, or necessarily embody apparatus for both adding and subtracting, and since predominantly the multiplying and dividing machines consist in essence of adding and subtracting mechanism, the invention is for brevity, described by making reference to a small type of apparatus intended primarily for adding and subtracting operations.

The foregoing and numerous other objects will be apparent from the following detailed description of the embodiment selected for purposes of disclosure, and my making reference to the accompanying drawings, in which:

Fig. 1 is a top or plan view of an adding and subtracting machine embodying the invention; Fig. 2 is an enlarged fragmentary view, showing certain parts in section, of the master or control mechanism made use of in the operation of my device, the location of Fig. 2 being identified by line 2—2 of Fig. 9; Fig. 3 is an enlarged section of the master control switch as viewed along line 3—3 of Fig. 2; Fig. 4 is a vertical longitudinal section of the forward portion of the device, showing one of the secondary solenoids together with its preselecting mechanism; Fig. 5 is an enlarged fragmentary longitudinal section of the forward portion of the device, and showing particularly certain of the preselecting and clearing elements; Fig. 6 is an enlarged fragmentary view of one of the preselecting buttons in operative position; Fig. 7 is a sectional elevation taken on line 7—7 of Fig. 6, and showing certain details of the construction of one of the preselecting switches; Fig. 8 is a section along line 8—8 of Fig. 6 and showing a preferred arrangement for retaining or holding one of the preselecting keys in operative position; Fig. 9 is an enlarged vertical transverse section of the device, taken along line 9—9 of Fig. 4; Fig. 10 is a fragmentary transverse section along line 10—10 of Fig. 5; Fig. 11 is a fragmentary transverse section along line 11—11 of Fig. 5; Fig. 12 is a section of the device along line 12—12 of Fig. 5; Fig. 13 is a fragmentary section along line 13—13 of Fig. 5; Fig. 14 is a fragmentary section along line 14—14 of Fig. 5; Fig. 15 is a fragmentary top or plan view of one of the secondary solenoid circuit breakers; Fig. 16 is a side elevation of the structure appearing in Fig. 15; Fig. 17 is a transverse section of the same mechanism, as viewed along line 17—17 of Fig. 16; 55

Fig. 18 is a top or plan view of the calculating or counter mechanism together with certain of the operating elements therefor, and showing a portion of the casing in horizontal section; Fig. 19 is a vertical section taken on the line 19-19 of Fig. 18; Fig. 20 is an enlarged vertical section of one of the calculating or counter units together with certain of its operating elements, all as viewed along line 20-20 of Fig. 19; Fig. 21 is an enlarged fragmentary vertical section of one of the calculating units and associated wheel or disc, and showing certain of the elements provided for resetting the device to a starting point after completion of a mathematical operation; Fig. 22 is a vertical sectional elevation as viewed along line 22-22 of Fig. 21; Fig. 23 is a vertical elevation showing certain parts in section and as viewed along line 23-23 of Fig. 21; Fig. 24 is a horizontal elevation showing certain parts in section and as taken along line 24-24 of Fig. 21, and Fig. 25 is a diagrammatic representation of the various electromagnetic units or solenoids, together with the associated switches and electrical conductors, and representing a preferred circuit relation or wiring diagram of the parts illustrated, when utilized with the mechanism illustrated by the preceding figures.

Referring now by characters of reference to the drawings, there is shown a casing 1, provided with a top or cover 2, a bottom designated at 3, side walls 4 and 5, and end walls which may be designated as front and rear walls respectively, and indicated by numerals 6 and 7. The top 2 is provided with a relatively raised area equipped near one of its ends with windows or apertures designated in order at 9A, 9B, 9C, 9D and 9E, these apertures being spaced laterally of the top (Fig. 1). Further carried by the top 2 of the casing are a plurality of rows of buttons or keys designated in order as A, B, C, D and E, the several rows of keys being spaced laterally of the top, and each row extending longitudinally thereof.

One of the buttons or keys in each row, for example at one end of the row, is designated by a suitable legend such as the letter C, designating it as a clearance button for that row. The remaining buttons or keys are shown as provided with legends, in the present instance numerals 50 in sequence from 1 to 9, both inclusive as shown, or may bear other insignia as may be required for the particular work to which the machine is adapted. In addition to the keys or buttons discussed, the top 2 also carries a key, bearing, for example, the letter G, and which in the example shown is used for general clearance, or clearing the machine as a whole. An additional button bearing the letter R is utilized in a manner corresponding to the usual repeating key 60 characterizing existing adding or calculating machines. The detailed function and operation of these buttons will be hereinafter described.

There is also carried by the top an elongated key or bar K, which serves to operate a switch 65 through which for certain modes of usage hereinafter referred to, electric current is supplied to the electrical and electromagnetic units herein-after referred to in detail. Parallel to one of the sides of the casing and carried by the top 2, is a bar M which extends longitudinally of the casing and serves to operate a master control switch for placing the machine in operation, all as hereinafter more fully described. It will be understood that in accordance with the present disclosure, each of the several keys, buttons and

bars, is adapted for movement toward and from the top of the casing, or otherwise expressed, is adapted for an approximately vertical reciprocating actuation, each of the keys and bars being returned to upward or inoperative position, and normally held away from the top 2 as by means of a suitable spring. Each of the number-bearing keys in the several rows A, B, C, D and E is provided with a shank or stem 11, preferably formed of insulating material, and which serves to position the associated spring 10, surrounding the stem, it further appearing that each of the key stems extends into the casing through a suitable aperture therefor in the top or cover 2.

Each of the numeral-key stems here in discussion, is provided with a slot 12 (Figs. 5, 6, 7 and 9) through which there extends a clearance rod, there being one such rod for each row of buttons or keys, these rods being numbered 13A, 13B, 13C, 13D and 13E, the letter suffixes corresponding with the letter designation of the associated row of keys or buttons. It will further appear that each of the key stems is provided with a pair of spaced projections or teeth 14, one of which is located on each side of the slot, these teeth projecting forwardly or in a direction toward the operator, and each being characterized by an inclined lower edge and a horizontal top or upper edge, so that when the key or button is depressed, the inclined edge will engage an adjacent pin or projection 15. A number of such elements 15 are carried by each of the clearance rods, to correspond to the number of keys associated with the rod. In the example of the disclosure there are nine such keys per row, although it will be understood that this number may be varied to meet different requirements.

Associated with each of the rods 13A, 13B, 13C, 13D and 13E, is a spring 16 by which the rod is held in operative position as shown by Fig. 5. Due to the biasing effect of the spring 16, it results that when a key is depressed, the inclined edge of the tooth or projection 14 carried by the stem 11 by which the depressed button is carried, will contact with an adjacent projection 15 and move that particular clearance rod in a forward direction until the stem 11 has been depressed sufficiently to bring the horizontal portion of the tooth below the projection 15. At this time the associated spring 16 will retract the rod, causing the pin 15 to ride onto the horizontal edge of the tooth and to retain the button in depressed position as is clearly shown by Fig. 6.

For purposes of returning the keys C, each is provided with a spring carried by its stem 17, the spring being designated at 18. The lower end of the key stem is bifurcated in form, so as to straddle the clearing rod associated with the corresponding row of keys, and further provided with teeth 19 which contact and coact with projections 20 carried by the associated clearing rod. The latter teeth are somewhat longer than the teeth 14, so that when the row-clearing key C is depressed, it will act to displace the rod longitudinally, in a direction forwardly of the machine, and will release any numeral key in the corresponding row which has been locked in depressed position. The tooth or projection 14 is of such a length that when the key C is fully depressed, its horizontal portion will not pass under the projection 20, but upon release of pressure on the key, both the key and rod return to their original or starting positions.

Provision is made for slidably mounting the rods 13A, 13B, 13C, 13D and 13E, by suitable

brackets 21 (Fig. 5) dependently carried by the top portion or cover 2 of the casing. Each of these rods has its forward end bent at a right angle as indicated by the numeral 22, these ends 5 making contact with levers 23 mounted on a rock shaft 24, journalled in the sides 4 and 5 of the casing 1. The rock shaft 24 has also secured thereto a lever 25, the free end of which extends into a slot 26 formed in the stem or shank 27 of 10 the key heretofore designated in Fig. 1 by the reference numeral G. For the purpose of returning the latter key to its normal or uppermost position, there is provided a spring 28 surrounding the stem 27, the upward movement of the key 15 G being limited by means of a pin or like element 29 located beneath the casing top 2. It will be noted that the corresponding rods 13A, 13B, 13C, 13D and 13E have their bent portions located forwardly of the levers 23, so that the rods are 20 enabled to reciprocate when influenced by any of the numeral keys or row-clearance keys; it will also appear that the operation of the general clearance key G will move all of the rods simultaneously, so as to effect a clearance of the entire 25 keyboard at one time, and will serve, when desired, to eliminate the necessity of operating all of the individual clearance keys C in the several numeral rows.

Extending transversely of the interior of the 30 casing is a shaft 30 on which are mounted a plurality of bellcrank levers 31, these levers corresponding in number to the number of clearing rods 13, and being independently movable or pivoted on the shaft 30. Each of the bellcrank 35 levers 31 is provided with an upwardly extending arm 32, the upper end of which is provided with an enlargement 33 in which is formed a slot 34. A pin 35 is carried by each of the clearance rods and projects laterally thereof into the slot 34 of 40 the associated lever 31, in such a manner that the rods 13 may be moved forwardly or to the left (Fig. 5), without actuating the associated bellcrank lever. Each of the levers 31 is also provided with an arm 36 which extends forwardly in 45 a substantially horizontal direction, and which normally contacts with a sleeve 37 slidably mounted on an arm 38 of an adjacent bellcrank lever 39, the levers 39 corresponding in number to the bellcrank levers 31. Each of the levers 39 50 also includes a downwardly extending arm 40, the purpose of which will be hereinafter more fully described. Each of the sleeves 37 above referred to is normally held in an extended position, as shown by Fig. 5, by a coil spring 41 carried by the arm 38 of the lever. Each of these sleeves is also provided with a projecting pin 37A which contacts the front edge of an associated lever 42, the levers 42 being fixedly mounted on a shaft 43 extending transversely of the casing 55 and conveniently mounted in its side walls. A single lever 44 is also secured to the shaft 43, and is slotted at its free end so as to receive the lower end of a stem 45 associated with the key or button designated by the letter R. This key is normally returned to and held in raised position by means of a spring 46, the upward thrust of which is limited by means of a pin 47 carried by the shank 45, and arranged to abut the under surface 60 of the top 2 at the upper limit of movement of the key and shank.

To permit passage through the top 2 of the stem 45, there is provided an elongated opening 48, the stem also being arranged to be retained in depressed position through the agency of a projection or tooth 49 adapted to engage the under

surface of the top 2 adjacent the slot 48, whereby the key R may be positioned in depressed relation. This effect is also contributed to by a bow spring 50 (Fig. 5) arranged to shift the stem in the elongated aperture therefor, when the key is depressed. The stem or shank 45 is provided near its lower extremity with a transversely projecting pin 51 which bears against the upper face of the lever 44, with the result that when the key R is depressed, the lever 44 will lock the shaft 43, causing the levers 42 to actuate the several sleeves 37 against their springs, and along the arms 38 of the bellcrank levers 39. It results from this that the sleeves 37 are removed from contact with the arms 36 of the bellcrank levers 31, thereby permitting the levers 39 to operate independently of levers 31. It is however the normal function of levers 39 to actuate levers 31, as will hereinafter more fully appear.

As a means of mounting the bellcrank levers 39, there is provided a shaft 39A which is mounted in brackets 52, the levers 39 being held against movement in one direction by means of a stop 53 formed on each of the brackets, and arranged to make contact with that arm of the lever 39 25 located adjacent the bracket.

Secured to the under surface of the top 2 of the casing, are a plurality of longitudinally extending strips 54. These are formed of insulating material and are so arranged in spaced relation on opposite sides of the stems or shanks 11 of the numeral-bearing keys, that the stems or shanks of the keys pass between the paired strips 54. The insulating strips serve primarily the purpose of mounting elements for the switch parts through which selected circuits are established incident to manipulation of the keys. The switches are secured to the strips, and so located as to be spaced on opposite sides, and extend into the path of the stem or shank of the key, which thus serves as the switch actuating member.

The switches associated with each of the key stems or shanks 11 consist of cooperating contact members 55 and 56 on one side of the stem, and 45 57 and 58 on the opposite side. By preference, the members 55 and 57 are formed of a resilient conducting metal, and are so arranged as to be moved outwardly and to contact respectively with the members 56 and 58 when the stem 11, 80 associated with a preselected key, is depressed.

Located in and disposed longitudinally of the casing are a plurality of solenoids 59A, 59B, 59C, 59D and 59E, one thereof being operatively related to the counting unit of each of the columns or rows of numeral-keys, the stationary portions of each of these solenoid assemblies being secured to the bottom of the casing. Connected at preselected points of the coil winding of each of the solenoids, are a plurality of conductors 60, 61, 62, 63, 64, 65, 66, 67 and 68, these conductors being in turn connected to the switch members 5 of that particular column or row of keys to which the given solenoid is functionally associated; for example, the solenoid 59A is connected to the switch member 5 in the row A of the numbered keys, the solenoid 59B to the row B of such keys, and so through the several columns or rows. It is to be noted that the conductors 60, etc., are all electrically connected to the rear portion of the associated electromagnet or solenoid, as will appear from Figs. 4 and 25.

The several switch members 55 of the row A of the number keys, have attached thereto conductors 69A, these conductors being secured to a 75

conductor 70A which is in turn connected to a contact 71A mounted in the stator 72 of a control switch. Similarly, the switch members 55 of the row B have conductors 69B connected thereto, the latter being in turn connected to a conductor 70B which is directed to a contact 71B in the stator 72. In a similar manner the switch members 55 in the row C are connected to a stationary contact 71C through the agency of conductors 69C and 70C.

In corresponding fashion, the switch members 55 in the row D are electrically connected to the contact 71D through conductors 69D and 70D, and switch members 55 in the row E, are connected to the contact 71E through conductors 69E and 70E.

Referring further to the sequence or control switch, the stator 72 therefor consists of an annulus or ring formed of insulating material in 20 and about which the contacts 71A, 71B, 71C, 71D and 71E are spaced at equal angles or distances. Within the stator is mounted a rotor element 73, also formed of insulating material, and which carries a conductor ring 74 on one of its faces, 25 being further provided with a contact brush 75 connected to the ring and projecting beyond the periphery of the rotor. As will appear upon rotation of the rotor the brush 75 will engage in sequence the stationary contacts carried by the 30 stator and heretofore described, in a manner progressively to complete electrical circuits to the switch members 55 in the rows A, B, C, D and E. The elements just described will best appear from Fig. 3 and their circuit relation best understood 35 from Fig. 25.

The rotor 73 is mounted on a shaft 76 (Fig. 3) which is journalled at one end in a bracket 77 dependently supported from the top 2 of the casing, and at its opposite end in a screw threaded 40 sleeve 78 carried, for example, by one of the side walls of the casing. A ratchet wheel 79 which is concentric or coaxial with the shaft 76, is fixed to the rotor of the switch, and is impelled in one direction of rotation by a pawl 80 pivotally carried on one face of a gear 81, loosely mounted on the shaft 76. This gear or pinion 81 normally enmeshes with a rack element 82 (Figs. 2 and 3), formed by preference of insulating material, and which forms part of the 45 support 83 for the armature 84 of a solenoid 85, provided for the purpose of operating the sequence or control switch M. As shown by Fig. 2, the armature 84 is normally returned in the position shown by means of a coil spring 86. In order to prevent a return of the solenoid armature 84 too quickly after the current in the 50 solenoid winding 85 is interrupted, there is provided a disc 87 slidably mounted on the shaft 76 (Fig. 3), and which is urged against the rotor of this switch by the coil spring 88, the loading of the spring being regulated by the threaded adjustment of sleeve 78 heretofore described. The frictional relation established through the spring between disc 87 and rotor 73, acts as a damping 55 agency for controlling the rate of return of the solenoid armature under the influence of the spring 86.

During the power movement of the armature 84, the rack 82 operates to rotate the gear 81 in 60 such a direction that the pawl 80 will ride over the ratchet wheel 79 without actuating the rotor, but upon the return movement of the armature, gear 81 will rotate in the opposite direction, and due to the engagement of the pawl 80 with the ratchet wheel 79 secured to the rotor 73, the 65

latter will now rotate, causing the contact brush 75 to traverse and sequentially to engage the contacts 71A, 71B, 71C, 71D and 71E. By preference, and in the example of the disclosure, the movement of the armature 84 and the rack 82 is sufficient to rotate the gear 81 substantially a complete revolution, or in any event, to an extent such that the contact brush 75 moves through an arc somewhat greater than that between the contacts 71A and 71E.

It will further appear from Fig. 3 that there is provided a contact brush 89, carried by a strip of insulation 90, the latter being in turn secured to the casing, and a conductor 91 serving to connect the brush 89 to the conductor 92.

The bar M of the master control switch is provided with a stem 93 formed of insulating material, by preference, the stem or shank 93 being embraced by a coil spring 93A, due to which the bar M is normally held in outermost or raised 20 position. Its upward movement is limited by means of a pin, or the like 94, extending through the stem 93 and contacting for purposes of limiting movement, with the under surface of the top 2.

Secured to the under side of the top 2 and spaced on opposite sides of the stem 93, are plates of insulating material 95 and 96 (Fig. 2), there being secured to the plate 95 switch members 97 and 98, the conductor 92 being connected 30 to the member 97 and a conductor 99 serving to connect the member 98 and one end of the winding of solenoid 85. Similarly, the plate 96 serves as a mounting for switch members 100 and 101, the former having connection with a conductor 35 102 and the latter to a conductor 103, the opposite end of which has a connection to the opposite end of the winding of solenoid 85. The switch members 98 and 101 are of spring material such as a resilient metal, and are brought 40 into contact with the members 97 and 100 when the bar M and so the stem 93 are depressed, whereby there is established a circuit through the solenoid 85.

Similarly to certain of the switch keys heretofore described, the key or button K referred to in connection with Fig. 1, is provided with a shank, stem or plunger portion 104, which projects through the top 2 of the casing, and which is normally kept in raised or circuit-opening position by a coil spring 105. The extent of upward or outward thrust of the plunger due to this spring, is limited by a pin 106 carried by the shank 104, and adapted to abut the under surface of the top 2. The shank 104 is further provided with a projection or tooth 107 arranged to be brought beneath the lower surface of the top 2, adjacent the shank aperture, so as to maintain the key in depressed position when desired, and so as to keep the supply circuit to the machine closed for as long a time as may be necessary without continued manual pressure on the key.

Extending along the under surface of the top element 2 and on opposite sides of the stem 104, 65 are insulating plates 108 and 109, the former serving to carry switch members 110 and 111. In similar manner there are secured to the insulating plate 109, switch elements 112 and 113, the latter being preferably of resilient or spring 70 metal, and so located as to be brought into contact with the members 110 and 112 respectively to depressing movement of the key or bar K. Conductors 110A, 110B, 110C, 110D and 110E are shown as secured one each to the in- 75

dividual members 110, these conductors 110A, 110B, 110C, 110D and 110E being in turn attached to the conductors 70A, 70B, 70C, 70D and 70E heretofore referred to and connected respectively to the stator contacts of the sequence or control switch shown by Fig. 3. A conductor 114 is electrically connected with the member 111, the element 114 either constituting or being connected to one leg of a feeder circuit for the electric system of the machine. The opposite leg 115 of such a circuit, is connected to the member 118, while the conductor 102 leads from the member 112 to the element 100 of the control switch. Connected to the conductor 102 is a lead 116, which serves in effect as a bus or trunk conductor, to the latter being connected branch conductors or leads 117A, 117B, 117C, 117D and 117E, these latter being connected respectively to the switch members 57 along the rows A, B, C, D and E of the numeral-bearing keys of the present disclosure. Attached to the switch members 58 of these rows are conductors 118, 119, 120, 121, 122, 123, 124, 125 and 126, there being one such conductor for each of the numeral key switches in each of the columns or rows, as will clearly appear from the wiring diagram of Fig. 25.

Referring further to the assembly and structure of each of the solenoids 59A, 59B, 59C, 59D and 59E, there is arranged for movement in each of the coils thereof, an armature or core 127. Each of such armatures is mounted on and supported by a guide rod 128, this rod being formed of insulating material and projecting beyond the ends of the solenoid core with which the armature is operatively associated. The portion 129 of the rod 128, projecting toward the forward part of the machine, is provided in its upper surface and near one end with a recess 130 (Fig. 5). Over this recess extends the free end of a leaf spring 131, the opposite end of this spring being secured to the portion 129. Mounted on the free end of this spring is a wedge-shaped cam, projection or tooth 132, so arranged that during the travel of the rod 128, particularly the portion 129 thereof, this projection will make a camming contact with the arm or lever 40 heretofore described (see Fig. 5). The parts are further so arranged that during the power stroke of the solenoid, the inclined face of this projection will contact with the arm 40, which being restrained from movement by the projection 53 on the bracket 52, will force the spring member 131 into the recess 130. However, on the return movement of the rod portion 129, the vertical face of the tooth or projection 132 will contact the arm 40 in a manner to rock the bellcrank lever 38-40, and will also actuate the bellcrank lever 31, moving the clearance rod to which the latter is connected, and thereby releasing any numeral key in the appurtenant row which may have been depressed, and at the same time permitting movement of the switch parts associated with such key, to switch-open position.

Secured to the bottom of the casing and extending forwardly from each of the solenoid assemblies, is a strip of insulating material 133, each of said strips being characterized by paired upstanding, parallel flanges or ribs 134 and 135. The latter elements are spaced inwardly from the longitudinal edges of each strip and parallel the path of travel of the rod portion 129 heretofore described. There results from the parallel relation and spacing of ribs 134 and 135, an intervening channel in which moves a projection

136, formed on the under side of the rod portion 129, and adjacent its outer or free end.

Carried by the strip 133 and outside of the rib 135, are a plurality of spring members 137 which correspond in number to the switch members 58, one of the members 137 being connected to the free end of each of the conductors 118, 119, 120, 121, 122, 123, 124, 125, and 126. The spring members 137 are angulate, preferably substantially L-shaped, and each carries on its vertical leg a contact plunger 138 which projects through an opening 139 in the flange or rib 135, preferably to a point substantially midway of the channel. Located on the strip 133 and on the outside of the rib 134, are angulately formed 15 spring members 140, each carrying a contact plunger or projection 141, each of these plungers extending through an opening 142 formed in the rib or flange 134. It is to be noted that the plungers last referred to are disposed opposite 20 the plungers 138, so that the paired elements 138-141 will be normally actuated in pair as the projection 136 is moved in spreading or deflecting relation therebetween. The flange or rib 134 is provided with apertured extensions 143 25 in the apertures of which is slidably disposed a rod 144, the latter having its front end 145 bent at an angle so as to extend in the path of the end of the rod portion 129, and so be abutted thereby when the rod approaches one end of its 30 path of travel. For the purpose of retracting the rod 144, there is provided a spring 146 (Fig. 5) which tends to bias the rod rearwardly when displaced as a result of operation of the solenoid to move the rod portion 129 to the outer limit 35 of its movement.

The rod 144 is also provided with a plurality of lateral projections 147 which are so spaced and arranged as to make contact with the rear edges of the upper portions of a number of levers 40 148, the latter being pivoted intermediate their ends to the flange or rib 134. The lower portions of these levers are biased forwardly by springs 149, but when the parts occupy the positions shown by Fig. 5, the levers are positioned 45 by the projections 147 on the rod 144. As will be seen from Figs. 12 and 17, the contact plungers 141 are each provided with a recess 150, which the lower end of the adjacent lever 148 is adapted to enter when the plunger or button 50 has been moved outwardly as shown. The purpose of this arrangement will be hereinafter explained in detail.

Attached to the L-shaped contact members 140, are conductors 151, 152, 153, 154, 155, 156, 55 157, 158 and 159, the opposite ends of these conductors being connected at preferably equidistant points along the solenoid winding in order commencing from the front end thereof, with the result that when the circuits are established, the 60 coil will be divided into a series of contiguous active zones, the first such zone being that portion of the coil between the conductors 60 and 151, the next between conductors 61 and 152, and so in the series through the coil, there being 65 preferably at least the same number of zones in each solenoid winding as there are numeral or character keys in the column or row controlling the given solenoid.

Referring further to the solenoid assembly, the 70 rear portion 160 of the rod 128 projects beyond the rear end of the associated winding or core, and is formed to provide a rack 161 on its upper face. This portion 160 is provided at or near its free end with a downwardly extending pro- 75

ection 162, to which is attached one end of a return spring 163, the opposite end of the spring being anchored, for example to the rear end of the solenoid. A stop 164 projects upwardly from the base or bottom of the casing and is located to be engaged by the projection 162, and thereby limit the travel of the rack in the direction of the return spring pull, the stop and projection, or one thereof, being provided with a cushioning element (not shown).

Each of the racks 161 meshes with a gear 165, which is rotatably carried by a sleeve 166 (Fig. 20). A pawl 167 is pivotally mounted on one face of the gear 165, and is adapted coactingly to engage with a ratchet wheel 168 formed on or secured to one face of a gear 169 which is also loosely mounted on the sleeve 166, and located on the pawl-bearing side of the gear 165. A second gear 170 is also loosely mounted on the sleeve 166, and on the opposite side of the gear 165. The gears 169 and 170 mesh with a pinion or gear 171 which may be of the type shown by Fig. 20, or may, if preferred, be a gear of bevel type. This pinion is rotatably carried by a boss 172 projecting upwardly from the base of the casing. The relation of the pinion to the gears 165 and 170 is obviously such as to compel the gears 169 and 170 to rotate in opposite directions when either is actuated. Secured to the ends of the sleeves 166 are gears 173 and 174, the gear 174 meshing with one of a plurality of gears 175 each carried by a face of one of a series of counting or indicating elements 176A, 176B, 176C, 176D and 176E. On the opposite side face of each counting element or wheel, is a segmental gear 177 (Fig. 22), which meshes through a stated or predetermined angle of its rotation with the gear 173, so as to turn the next adjacent counting wheel through an angle, for example, one tenth revolution, corresponding to the next higher member or character. When, in the case of numerals, the next higher number is to be attained than is carried by a given counter or wheel, as for example when the numeral 9 is reached on the wheel 176A and this element is operated one step farther, the segment 177 engages the gear 173 of the group of gears operating the wheel 176B, and rotates it so as to bring into view the numeral 1, through the window in the top of the casing, while a cipher appears on the wheel 176A. It is to be understood that there is a separate group of gears for the operation of each counting unit as shown in Fig. 18, it being also understood that the gear 173 is preferably omitted from the gear unit or group identified with the end counter of the series, in the disclosed example, the counting wheel 176A, as such element would have no function in this group.

Extending through each of the sleeves 166 is a short shaft or shaft section 178, which is connected to the short shaft in an adjacent set of gears or sleeve in such a manner that while each of the short shafts is capable of independent rotation, they all may be moved or shifted simultaneously in a longitudinal or an axial direction. Each of the shaft sections is provided with pins 179 and 180 which are of such length as to extend through slots 181 and 182 formed in the sleeve 166, and have their ends projecting beyond the sleeve (Fig. 21). The pins 179 and 180 are designed to be moved into and out of recesses 183 and 184 formed in the gears 169 and 170, respectively, by movement of a knob 185 located outside of the casing. This movement of the knob serves to lock the sleeve 166 and gears 173

and 174, with one or the other of the gears 169 and 170 as desired, which will thereby control the direction of rotation of the counting or computing wheels, due to the fact that the gears 169 and 170 are compelled, as heretofore noted, to rotate in opposite directions. By this provision the preselected forward or reverse gear can be interlocked with the gears that operate the counting or computing wheels. It is to be understood that while the shaft sections can rotate freely, independently of each other, the connections between the shaft sections are such that a substantially rigid or unitary sectional shaft results so that bearings therefor are required only at each end of the composite shaft assembly. 15

The counting units identified with wheels 176A, 176B, 176C, 176D and 176E are provided with hubs 186 and 187, projecting from opposite sides of the wheels, the hubs 187 each being provided with a notch 188. The counter or computing 20 wheels are loosely mounted on a hollow shaft 189 which has openings 190 therethrough, these openings being adapted to register with the notches 188 in the hub 187.

Within the shaft 189 are secured a plurality of 25 angulate spring members 191 which have their short ends projecting slightly into the openings 190, and interiorly of the hollow shaft is located a shaft 192, provided with longitudinally spaced enlargements, collars or camming members 193, 30 equal in number to the spring members 191. The hollow shaft 189 is provided at one end with a closure or plug 194, through which the shaft 192 projects, and to the projecting end of the shaft is pivoted a crank handle 195, provided with a fulcrum projection or lug 196 which rides on a ring 197 conveniently projecting from the side 5 of the casing.

Formed on the shaft 192, and spaced inwardly from the end of the side 5 of the casing is a 40 collar or projection 198 (Fig. 21), which is slidably secured to the hollow shaft 189 as by a key 199. A spring 200 is disposed between the collar and the closure or plug 194, this spring tending normally to bias the collar away from the closure, and thereby tending to tilt the crank handle 195 into the position shown by Fig. 18. 45

As will have appeared, the purpose of the structure just described is to reset the counters or counting wheels 176A, 176B, 176C, 176D and 176E, to a zero reading. To effect this resetting operation, the handle 195 is moved into the position shown in Fig. 21, that is with the shank of the handle at about a right angle to the element 192. This movement of the crank serves to displace the shaft 192 longitudinally in a direction to the right (Fig. 21) and thus causes the enlargements or camming members 193 to bear against and outwardly deflect each of the springs 191. With the shaft 192 in this extended position, the handle may be turned in either direction, and as the openings 190 are brought into register with the notches 188, the angulate ends of the springs 191 enter the notches and cause the counters or counting wheels to rotate directly 60 with the shafts 192 and 189. Since the notches 188 are so formed and located as to work opposite the same number or character on each of the counters or counting wheels, it will appear that only one complete revolution of the crank 65 is necessary to align all of the counting wheels in a manner to restore them all to the same or a zero reading. Upon releasing the handle, the spring 200 again shifts the shaft 192 along its axis, bringing the enlarged portions 193 out of 70 75

contact with springs 181, which then move inwardly and retract from the notches 188, following which the counters are again independently movable and available for further totalling or calculating operations.

Referring again to the assembly of Figs. 20, 22, 23 and 24, it will be noted that the gears 174 and 175 are always enmeshed, as are also the gear 165 and rack 161. From this there results a prevention of any tendency of the counters to overrun when actuated for totalling or other calculating purposes; the gears and wheels, with the exception of gears 165, also fit rather snugly on their respective shafts or sleeves, so as to obviate any tendency to excess movement or spinning after the action of the rack 161 has ceased.

While the operation of the different parts, and hence of the assembly of the device, is thought to be obvious from the foregoing description of the elements and their several purposes, the function and use of the mechanism as a whole may be briefly reviewed as follows:

The conductors 92 and 102 are connected in a well understood manner to a source of electrical energy (not shown), as through the conductors 92A and 92B. One example of a convenient and usual form of connection, is one of the cord and plug type, which being well known in the electrical arts, need not be described in detail.

Conductors 92 and 102 will serve to supply electric energy to the switch members 97 and 100, respectively, of the master control switch, and at the same time the brush 89 is energized through conductor 91, as are the switch members 57 identified with each of the columns or rows A, B, C, D and E.

Assuming now by way of example, that the operator desires to add numbers 185 and 1029; he will first depress the key in row A bearing the numeral 5, such key being releasably retained in depressed position by the clearance bar for that row. The next operation takes place in row B, where the key bearing numeral 8 is depressed, and thereafter in similar manner, key No. 1 in row C. Following this, the bar M is depressed to close the circuit between the switch members 97 and 98, and between members 100 and 101. This will actuate the solenoid 85 with the effect of drawing the armature 84 and rack 82 against the action of the spring 86. However, because of the effect of the ratchet 79 and pawl 80, the rotor 73 is not yet moved, but upon releasing the bar M, the bar moves upwardly under the influence of its spring 93A, and the circuit through the solenoid 85 is broken, following which spring 86 initiates the movement of rack 82 and the armature back to their starting positions. During this phase of the operation, the ratchet and pawl come into action and operate the switch rotor, it being noted that the ring 74 is energized through the brush 89. As the rotor commences to move, the brush 75 will first come into contact with the stationary contact 71A of the stator which will serve to complete the circuit through the conductor 70A, thence into the conductor 69A, thence through switch parts 55 and 56 adjacent the key 5, thence through the conductor 64 of the solenoid coil. Current is taken from the coil through the conductor 155, thence to the button 141, button 138, conductor 122, the switch members 58 and 57, conductors 117A and 116, and thence through conductor 102 and through the main conductor 92B. When the circuit has been thus completed,

the armature of the solenoid moves into that zone of the solenoid coil which has been energized. In the example given, such energized zone will consist of that portion of the winding between the points of connection of conductors 64 and 155. When the armature or core of the solenoid is moved into this zone, it also moves the rack 161 to a degree to operate the group of gears of the counter assembly to rotate the numeral or counting wheel to an extent that the numeral 5 shows through the window 9A, corresponding to the column or row A. During the described movement of the armature and rack of the solenoid associated with row A, the rod portion 129 bearing the projection 136 has also been in motion. The first step of the latter movement is to release the end 145 of the bar 144, permitting the spring 146 to move the bar or rod 144 and thereby release the upper ends of the several swingable levers 148 associated with the given assembly.

As has been previously noted, the projection 136 traveling in the channel between the ribs or flanges 134 and 135 serves to force apart the paired plungers or buttons 138 and 141, as it passes these elements. As they are thus forced apart, the springs 149 will cause a movement of the lower ends of the levers 148 into the notches 150. This operation is continued until the projection has separated the plungers to which the conductors 155 and 122 are attached. At this time the circuit through the winding of the coil is broken, following which the spring 163 will initiate the return movement of the armature to its starting position. As the armature nears the end of its return travel, the projection or tooth 132 makes contact with the arm 40 of the bellcrank 39, causing it to rock the bellcrank lever 31, which, in turn, will draw the clearance rod forward and release the button or key that has been theretofore depressed, and will also serve to open the switches that have been closed by depression of such button.

As the armature approaches or attains the end of its return stroke, the end of the rod portion 129 engages the bent portion 145 of the rod 144, moving it longitudinally, and causing the projections 147 to rock the levers 148 and to release the plungers 141 which have been held thereby. At this stage the operation of elements in response to actuation of the key in row A, has been completed. By this time the rotor brush has moved sufficiently to reach the contact 71B, where the circuit is completed through the solenoid winding zone controlled by the key bearing the numeral 8. Since the action resulting from and subsequent to the closing of the electric circuit through 71B is the same as described in connection with the row A, with the exception of the extent of armature travel, the subsequent movements need not be described in detail. The switch rotor next closes the circuit through the contact 71C where the same operations are completed. This will clear the keyboard as only three keys have been depressed and the machine is ready for the next setup or calculating operation.

To effect the next operation the operator depresses the key 9 in column or row A, key 2 in row B, none in row C, as the zero appears in that row, and key 1 in row D. The numerals 1, 8 and 5 have appeared in their respective windows and the solenoid 85 is again in its starting position. The bar M is again depressed, closing the control switch, and will again operate

the solenoid 59 and the master control switch. As the solenoid 59A is energized, the gear groups operated by the rack 161 of the associated solenoid, will again operate the counters or wheels 176A through an angular distance corresponding to 9 numerals. Otherwise expressed, the accumulation of the nine additional stages of movement will bring the count in the unit, to a total of 14. As the zero or cipher on the wheel 176A passes the window 9A, the segment 177 on that wheel engages the gear 173 of the next gear group and serves to move the counter wheel 176B through, say $\frac{1}{6}$ of a revolution. The solenoid 59A then completes its cycle of operation as previously described in clearing row A. In the example given, the solenoid 59B next is brought into action and serves to actuate the wheel or counter 176B through two additional points. In so doing, the segment 177 on the wheel 176B comes into engagement with the gear 173 of the group operated by the solenoid 59C, and moves it one point. The solenoid 59B then completes the cycle and clears the row B.

Since in the example given the solenoid 59C should retain its initial or zero reading, this coil is not energized by the master control switch, no key having been depressed in the row C corresponding to this coil. In sequence, the master control switch then closes the circuit in the first zone of the solenoid 59D and the numeral 1 appears in the window corresponding to the row D. From the foregoing it will appear that when the described operations are completed, the numerals 1, 2, 1, 4 appear through the windows corresponding respectively to the rows D, C, B and A, this number being the sum of 185 and 1029. Assuming no further addition to be desired and no other operation contemplated, the wheels or counters 176A, 176B, 176C, 176D and 176E are reset to zero or initial reading in the manner previously described, through the manipulation of the crank 195 and associated resetting elements.

When the device is to be utilized for additive operations in the manner described, the knob 185 (Fig. 18) is brought to occupy its inward position as represented by solid lines (Fig. 18) under which condition the gear 169 is engaged with the pin 179 and forms the driving element for operating the group of gears. When, however, the knob 185 is drawn outwardly, the gear 170 is engaged with the pin 180 and becomes the driving element of the gear group; however, as this gear is driven through the pinion 171 it always rotates in a direction opposite that of the gear 169, from which it will appear obvious that the counters 176A, 176B, 176C, 176D and 176E are driven in a direction the reverse of that noted in connection with the operations of addition, but in response however to the same movement of the rack 161 and armature or core of each solenoid.

In the event the operator should depress the wrong key in any one of the columns or rows, his mistake may be easily rectified by pressing the key marked C, in the row in which the error has been committed; the effect of the depression of the row-clearance key is, as before referred to, to shift the clearance bar for that row, and to release, prior to any effect in the totaling or other calculating mechanism of the machine, the key that has been incorrectly depressed.

Should it be desired to clear all of the rows without operating the solenoids or without requiring manipulation of all of the row-clearance

keys, key G, being the general clearance key, is depressed. This movement serves to actuate the lever 25 in a manner to rock the shaft 24 and in turn the levers 23 in a manner to move simultaneously, all of the several ray-clearance bars and thereby to release all of the depressed keys by means of a single manipulative operation.

Should it be desired to repeat the same numbers in the various rows, the repeat key, designated at R, is depressed, the effect of this being to move the arm 44 downwardly, rocking the shaft 43 and causing arms 42, mounted on this shaft, to shift the sleeves 37 forwardly and out of contact with the arm 36 of the bellcrank lever 31. At this time the operation of the arm 40 of bellcrank lever 39, under the influence of the projection or tooth 132, will be without effect on the bellcrank lever 31. From this it results that the clearance rods are not operated by the actuation of the electromagnets or solenoids, until the repeat key is again released.

It will be understood that after each cycle of operations of the solenoid 85, bar M, serving to close the circuit through the control switch, must again be depressed in order to initiate a new cycle of operations.

The speed of the rotor 73 is so controlled through the agencies described, that the brush 75 engages the contacts 71A, 71B, 71C, 71D and 71E, at least for a sufficient time during the movement of the rotor, to permit a full stroke of the solenoids controlled through the several contacts. If desired, a somewhat longer period or interval is permissible, since the circuit through the solenoid coil is broken by the separation of the plungers 138 and 141 as the armature attains the preselected zone of the associated coil or winding.

It will be noted that the gear 81 and gears 165 serve to set into operation the parts associated therewith, only when rotating in one direction, the rotation in the opposite direction as influenced by the reciprocatory movement of the associated racks, being an idle or return rotation, and performing no work.

It will also be noted that it is entirely possible and feasible so to dispose the parts of the counter gear units, that such units when operated by the solenoid racks, will function either on the power stroke or on the return stroke of the solenoid armature, without departing from the intended scope of the invention, this change being effected as may be desirable in certain instances, by reversing the ratchet and pawl mechanism through which is driven the gear 169.

One important feature of the present assembly consists in dividing the windings or coils of each of the solenoids 59A, 59B, 59C, 59D and 59E, into zones which are selectively energizable by the actuation of selected keys in the rows A, B, C, D and E. By this provision, the extent of rotation imparted to each of the counter gear groups by the solenoid of that group, is accurately controlled and effected as a result of depression of a numeral key, with a minimum of parts and mechanism.

Another noteworthy feature of the present construction consists in the interruption of the solenoid circuit through the coil zone when the armature has reached that zone, this being accomplished through the limit switch means described, this result being attained independently of the control switch. There is thus established a maximum interval of energization of the desired portion or zone of the solenoid coil, which

would not be the case were the energization of the coil dependent upon the time during which the operator held in depressed position, a given numeral-selecting key or like control.

6 It may further be mentioned that after a selection is made, through the column keys, of a zone of one of the solenoids to be energized, the circuit through that zone is not completed until the rotor 13 is operated to a given position, and that 10 as soon as the armature is brought to occupy the preselected zone, the circuit is again broken due to the separation of the plungers or buttons 138 and 141, these elements being maintained in separated or circuit-opening relation until after the 15 key utilized in making the zone selection has been cleared. This arrangement obviates any possibility of the solenoid acting more than once during the period of passage of the brush 75 over the stator contact corresponding to the particular 20 solenoid.

For effecting certain classes of addition or other calculating work, it may be desirable to accelerate the action of the solenoids 59A, 59B, 59C, 59D and 59E, in such a manner that the device 25 will operate to accumulate or total, and will function for other operations, without employing the control switch and solenoid 85 shown by Fig. 2. Under this form of usage, the counting or calculating units are instantly responsive to depression 30 of the numeral keys in several rows of columns. When desired for this form of usage, the switch controlled by the button K is closed, this switch having been first directly connected to the feeder circuit or source of electrical energy. The 35 closing of this switch will serve to energize the switch members 55 and 57 in each of the rows A, B, C, D and E. As a consequence, when one of the keys in the row E, for example, is depressed, the circuit is established through the 40 zone of the solenoid 59E which has been selected by the depressed key, and the armature 127 is advanced into that zone, so that the proper figure is almost instantly presented through the window 9E without any delay which might otherwise 45 be incident to the movement of the control switch rotor as operated by the solenoid 85. For example, after the key bearing the numeral 2 is depressed, members 55 and 57 being energized, will serve immediately to energize the switch 50 members 56 and 58 respectively. By reason of the conductors 61 and 152, that portion of the solenoid winding to which they are attached, and the plungers 138 and 141, the circuit is completed and so remains until the solenoid armature has 55 operated to an extent to cause the plungers 139 and 141 to be separated by the projection 136. Since the projection 132 operates the clearing mechanism before the rod 144 is retracted to operate the levers for releasing the limit switch 60 plungers that have been forced apart thereby, it will be seen that the solenoid 59E will be operated only once in response to a single depressing movement of any of the numeral keys.

It is further to be noted that when the key K 65 is depressed, it is retained by the projection or tooth on the stem 104, with the result that the switch members 110 and 111, and 112 and 113 remain in contact or in circuit-closing relation. When this switch is thus closed, it will be noted 70 that two or more of the solenoids which operate the counters or counting gear units, may be so operated simultaneously, which is not possible when the control switch identified with Fig. 3, is utilized. When the operator is availing himself 75 of this mode of operation, it may be noted as

advisable that the keys selected in the several columns or rows, be depressed in order from right to left, so as to assure the correct functional relation between the adjacent counting units of the several rows.

Many of the details of the wiring, placement of conductors within the casing and connection thereof to the switches and switching units will be obvious to those skilled in the electrical arts, and require no detailed description. Among 10 such provisions there may be mentioned a preference for the disposition in the casing, of an electrical receptacle to which conductors 92A and 92B are attached, and a similar receptacle for conductors 114 and 115. These elements 15 may be of a type adapted to receive detachable plugs or some other suitable form of appliance connection. It is in any case obviously desirable to locate all or substantially all of the wiring 20 connections interiorly of the casing.

While the invention has been described by making detailed and specific reference to a simplified embodiment thereof, and in the interest of brevity, has been described by reference to a machine primarily to be utilized for addition 25 and subtraction, the specification is to be understood solely in a descriptive and not in a limiting sense, since many changes may be made in the parts, their arrangements, their combinations, their circuit and wiring arrangements, as well as 30 in the purposes and uses of the device, all without departing from the spirit and full intended scope of the invention as defined by the appended claims.

I claim as my invention:

1. In a calculating machine, key-controlled differential mechanism for translating effective key actuations to an accumulator device, said mechanism comprising a plurality of number selecting keys, a plurality of switches functionally connected to the keys, an electromagnet in circuit with said switches and a source of energy, the electromagnet being characterized by a single, tapped winding providing a plurality of selectively energizable zones of substantially equal magnetic extent, an electromagnetic element reciprocal in said electromagnet winding and operatively connected to said accumulator device, said winding and switches being so connected in circuit as to control the zones of energization of the winding, and therethrough, the extent of actuation of said electromagnetic element, a limit switch for each energizable zone of said winding, operable by the electromagnetic element, latching means for the limit switches, latch-releasing means operable by said element, and key-releasing means operable by said element upon attaining a predetermined position.

2. In a calculating machine, key-controlled differential mechanism for translating effective key actuations to an accumulator device, said mechanism comprising an electromagnet including a continuous, tapped winding providing a plurality of energizable zones of substantially equal magnetic extent, an armature reciprocal in said winding and operatively connected to said accumulator device, a plurality of control keys, a plurality of switching devices arranged for operation by the control keys, and in circuit with the tapped winding so as to permit energization 60 of the magnetic zones thereof one at a time, an additional plurality of switches in circuit with said tapped winding, said switches being operated by the armature in one direction of its movement, to limit the energization of said winding 65 70 75 76

zones, irrespective of the closure of the key-actuated switching devices, and means operable by the armature during its movement in the opposite direction, for restoring the control keys and switching devices to switch-open position.

3. In a calculating machine, key-controlled differential mechanism for translating effective key actuating movements to an accumulator device, said mechanism comprising a plurality of selectively operable keys, an electric switch operable by each of said keys, an electromagnetic device, including a continuous, tapped winding in circuit with said switches and a source of energy, said winding providing a plurality of energizable zones of substantially equal magnetic extent, each zone having its energization under the control of one of said key-operated switches, an armature reciprocably movable in said winding and operatively connected to said accumulator device, means under direct control of the armature for terminating the energization of any given zone of said winding as the armature is actuated to and attains such zone, and means operable by said armature for restoring to inactive positions, the key and its control switch effecting the energization of said given zone.

4. In a calculating machine, key-controlled differential mechanism for translating key actuating movements to an accumulator device, said mechanism comprising a plurality of control switches, a manually operated key for actuating each switch, an electromagnet winding, tapped to provide a plurality of energizable zones of substantially equal magnetic extent, said winding being in circuit with said switches such that each of the energizable zones thereof is controlled by one of said switches, an armature associated with said winding and operatively connected to said accumulator device, switching means caused to terminate energization of the winding zones by the armature upon completion of a predetermined range of its movement, and means operable by the armature for causing a restoration of the previously operated keys and switches actuated thereby, to inactive positions.

5. In a calculating machine, mechanism for translating the effect of key setting movements to an accumulator device, the mechanism including a plurality of key-influenced switches, an electromagnetic winding characterized by selectively energizable zones of substantially equal magnetic length, controlled respectively by said switches, armature means associated with said winding and operatively related to the accumulator device, a limit switch in circuit with each of said winding zones, the limit switches being disposed for sequential actuation by said armature means upon attaining successive predetermined positions, and operable to de-energize the winding zones irrespective of position of the key-influenced switches, and an armature-actuated device for restoring the last said switches to open position.

6. In a calculating machine, mechanism for translating the effect of key setting operations to an accumulator device, the mechanism including an electromagnet winding tapped to provide a plurality of energizable zones, key-actuated switches each in circuit with one of said winding zones, an armature for said winding operatively related to the accumulator device, limit switches each in circuit with one of said winding zones, said limit switches being operable to open-circuit positions by the armature upon its attaining successive predetermined positions, means for latch-

ing each limit switch in circuit-open position as it is actuated thereto by the armature, means for releasing the latching means when the armature has attained a predetermined position in its path, and means operable by the armature for restoring the key-actuated switches to circuit-opening position.

7. In a calculating machine, including selecting keys and accumulator mechanism, a device for translating the effect of key setting movements to the accumulator mechanism, the device including a key-influenced electromagnet, an armature therefor operatively related to the accumulator mechanism, a limit switch in circuit with the electromagnet and operable responsively to the armature upon attaining a predetermined position, a latch arranged to retain the limit switch in circuit-open position when opened by movement of the armature, and latch tripping means operable responsively to movement of the armature into a predetermined portion of its path of travel.

8. In a calculating machine, key-controlled mechanism for translating the effect of key setting movements to an accumulator device, said mechanism including a plurality of control keys, switch means operatively related to each of said keys, an electromagnetic device including a reciprocable armature operatively connected to said accumulator device and an energizing winding for said armature, said winding being characterized by a plurality of energizable zones each in circuit with one of the key-actuated switch means, latch means for retaining the keys in actuated positions and the associated switch means in closed positions, and latch tripping means operable by the armature in one direction of its movement.

9. In a calculating machine, key-controlled mechanism for translating the effect of key settings to an accumulator device, said mechanism including a plurality of control keys, switch means operatively related to each of said keys, an electromagnetic device including a reciprocable armature operatively connected to said accumulator device and an energizing winding for the armature, said winding being characterized by a plurality of energizable zones each in circuit with one of said switch means, latching means associated with the keys and adapted to retain them in actuated and switch closing positions, a trip lever associated with the latching means and a cam element operatively associated with said armature, the cam element being formed and arranged to actuate the trip lever responsively to movement of the cam element and armature in one direction in a restricted portion of the path of travel thereof, and to clear the trip lever when moving in the opposite direction.

10. In a calculating machine, key-controlled mechanism for translating key settings to an accumulator device, said mechanism including a plurality of keys, switch means operated by each key, an electromagnet winding characterized by a plurality of energizable zones of substantially equal magnetic extent, the energization of each zone being controlled by one of said key-operated switch means, an armature functionally associated with said winding zones, spring means arranged to urge said armature to an initial position, said armature being operatively connected to said accumulator device, a projection on said armature, normally closed limit switches each in circuit with one of said energizable zones of the winding and located in the path of travel of said armature projection, means on said projection

operable in one direction of armature travel to open-circuit said limit switches, whereby to effect deenergization of said winding zones, and means operated by the armature on its return movement to said initial position under the influence of said spring means, effective to restore said limit switches to closed positions.

11. In a calculating machine, key-controlled mechanism for translating effective key movements to an accumulator device, said mechanism including a plurality of keys, switch means operated by each key, means for releasably latching said keys and associated switch means in switch-closed positions upon key actuation thereto, an electromagnet winding characterized by a plurality of energizable zones of substantially equal magnetic extent, the energization of each zone being controlled by one of said key-operated switch means, an armature functionally associated with said winding zones, spring means

arranged to urge said armature to an initial position, said armature being operatively connected to said accumulator device, a projection on said armature, normally closed limit switches each in circuit with one of said winding zones and located in the path of travel of said armature projection, means on said projection operable in one direction of armature travel, for open-circuiting said limit switches, whereby to effect deenergization of said winding zones, means operated by the armature on its return movement to said initial position under the influence of said spring means, effective to restore said limit switches to closed positions, and additional means operable by said armature on its return movement to initial position, to release said key latch means, whereby to restore said keys and associated switch means to switch-open positions.
